UNITED STATES PATENT OFFICE.

GEORGE H. FORSYTH, OF CHICAGO, ILLINOIS.

CAR-WINDOW CONSTRUCTION.

1,274,028.

Specification of Letters Patent. Patented July 30, 1918.

Application filed May 17, 1915. Serial No. 28,546.

To all whom it may concern:

Be it known that I, GEORGE H. FORSYTH, a citizen of the United States, residing at Chicago, in the county of Cook and State 5 of Illinois, have invented certain new and useful Improvements in Car-Window Construction, of which the following is a specification.

The purpose of this invention is to provide 10 a window frame construction comprising a bottom sill member or window stool preferably provided with a suitable incline and step for the sash, and having the ends of said sill member turned upwardly and extending, if desired, clear up to and preferably beneath the letter-board of the car, the latter also being preferably fastened to the 15 top ends of the side members and serving as a tie member for the latter. Either the 20 lower margin of the letter-board itself can be turned inwardly at the window openings to provide suitable top finish, or a separate top finish cross member can be provided between side frame members and a straight 25 letter-board employed, the said finish member lying preferably within the lower margin of the letter-board and forming in effect a part thereof.

This design of window frame is much 30 cheaper of manufacture than where the frame is pressed up out of a sheet of metal into a box-like structure, the said pressing then having to be blanked out to form the window opening as well as the inwardly 35 turned flange at the top to allow for the upward movement of the sash.

I show several modifications of the above 40 window frame structure, including, as stated, a separate finish member for the top of the frame; and this finish member can either extend to the side members of the frame or its vertical face ends can be extended laterally so that they will lie between the letter board and the upper ends of the 45 side members of the frame. In the latter case, the tops of the side members of the frame can be riveted to the finish member and through it to the letter-board. On the other hand, if desired the top finish member 50 need only extend to the side members of the frame.

I have shown a preferred method of forming 55 this window frame, in which the member to be formed into the window frame is an angle section. The latter is placed centrally on the top of a die block whose width

is that of the desired window frame, and whose top surface is provided with the proper formation to produce the incline for the sill and the step for the sash. The punch 60 constituting the upper die member comprises a block having a preferably shallow depression, whose cross wall is likewise provided with proper formation to assist the lower die to produce the proper incline and 65 step for the sill. These die members are rounded off so that all edges and ends and corners of the sill formation will be generously filleted. When the punch is forced 70 downwardly, not only is the sill formed centrally in the angle, but also the sides of the angle are forced downwardly to form the side members of the window frame, the frame thus being formed upside down.

It must be evident, especially when the 75 side vertical members extend upwardly only a limited distance, that the window frame structure can readily be formed up out of a flat sheet of metal instead of out of an angle section.

If desired the side members of the window 80 frame pressing need only extend upwardly a limited distance to preserve the advantages of the sill or stool formation. These advantages consist not only in the provision of a 85 much stronger window frame, but also in the elimination of rust and consequent deterioration at the bottom corners of the usual built-up car window openings formed by over-lapping or abutting members which 90 open up, particularly under the movement of the car, which causes the paint to break at such points, thereby permitting the entrance of moisture.

To a substantial extent the advantages of 95 this window frame structure would still be preserved even if the side flanges of the vertical members were omitted. It should therefore be understood that I do not limit the scope of this invention to the details of 100 construction shown.

In order that the invention may be readily understood preferred and modified embodiments of the same are set forth in the accompanying drawings and in the description 105 based thereon, it being understood that the drawings and description are to be taken in an illustrative rather than in an unnecessarily limiting sense. In the drawings—

Figure 1 is a front elevation of so much 110 of the car window as includes a window frame embodying the invention;

Fig. 2 is a horizontal section on the line 2—2 of Fig. 1;

Fig. 3 is a vertical section on the line 3—3 of Fig. 1;

Fig. 4 is a similar section on the line 4—4 of Fig. 1;

Fig. 5 is a detail view of a modified corner of a frame;

Fig. 6 is a vertical section on the line 6—6 of Fig. 5;

Fig. 7 is a view similar to Fig. 5 but showing a slight modification;

Fig. 8 is a vertical section on the line 8—8 of Fig. 7;

Fig. 9 is a section similar to Fig. 3 but of a modification;

Fig. 10 is a vertical section through the lower portion of a window showing the formation of the window sill in its relation to the sash and to the belt rail of the car;

Fig. 11 is a horizontal section on the line 11—11 of Fig. 10;

Fig. 12 is a diagrammatic view illustrating the method of forming the window frame;

Fig. 13 is a horizontal section through one of the side members of a slightly modified form; and

Figs. 14 and 15 are detail vertical sections through the upper portion of the lintel and sash showing the insertion of a filler block and weather strip.

In the drawings the window frame is shown as comprising the horizontal sill or stool portion 21—21^a and the upright side frame members 22 formed integral therewith and the junction therebetween generously filleted in the angle as indicated at 23. The upper ends of the side members 22 are tied together by means of the letter-board 24 either directly by being riveted thereto as illustrated in Fig. 3 or indirectly by the interposition therebetween of a finish member 25, the lintel of the window being formed in the one case by an inwardly deflected portion 24^a of the letter-board itself, or by the deflected portion 25^a of the finish member. Preferably the window frame is divided centrally by a vertical window post

26 which is connected to the letter board as shown in Figs. 3 and 9 according as to whether the lintel of the window and post is formed by the deflected portion of the letter board or finish member. The lower end of the post rests upon the sill and is connected thereto as indicated in Fig. 4 by means of a filler member 27 disposed within the hollow post and secured to the sill as by welding or riveting as indicated at 28 and to the front wall of the post by means of the rivets 29.

To form the connection between the side members 22 of the window frame and the letter-board at the upper corners of the frame the front face 22^a of the side frame is

preferably extended upwardly behind the letter-board and riveted thereto as indicated at 30. Where the finish member 25 is employed it may terminate at and abut against the side member 22, as indicated in Figs. 5 and 6, or it may extend beyond the latter as indicated in Figs. 7 and 8, and a portion of the rivets 30 may pass through the three members 22^a, 24, 25, (Fig. 8).

Above the lintel, indicated at 24^a and 25^a, a filler block 31 may be inserted carrying a weather strip 32 bearing against the sash member 33, as indicated in Figs. 14 and 15.

The window frame in the course of production is formed by an angle beam indicated in dotted lines at 34 in Fig. 12, said beam being shown as of L-formation with a flange 35, although a different cross section may be employed depending upon the conformation of the frame desired to be produced.

Heretofore it has been usual where car window frames are composed of integrally formed members to blank out for the window opening and for the movement of the sash, making an expensive operation of many steps and resulting in great waste of the material blanked out. I simplify the operation and save waste by forming the window frame from an angle beam in the pressing die acting upon the material transversely of its length to fold the same into a U-shape, the bottom of the U constituting the sill and the vertical portion of the U constituting the upright side members of the frame. In the pressing of the frame die members are employed having such a conformation as to produce the step 21^b and straighten the flange 35 to form a forward extension 21^c of the sill, said flange retaining its shape at the sides to form the face plate 22^a of the side frame members. The lines of junction between the sill and side frame members are generously filleted as previously stated so as to obviate any sharp angles.

The dies may be so formed as to bend the material inwardly as indicated at 36 in Fig. 13 to form an integral window stop where desired.

The portion 21^a of the sill and the forward extension 21^c overlie the belt rail 37 of the car and the overlapping portions of the various parts are protected from the entrance of moisture by means of a finishing sheet 38 which not only overlies the face plate 22^a and the sill extension 21^c, but also is downturned as indicated at 39 in Fig. 10 so as to seal the division line and the space which would otherwise appear between the said sheet and the car side between the successive window frames.

It should be noted that not only are the longitudinal and transverse angular bends of the sill and the side members very generously filleted but that the corners formed by the

sill and side members are also well filleted, as shown at 21^a.

Also it should be observed that the front face of the central upright member 26 lies back of the plane of the front faces of side members 22, the said member 26 being curved or filleted at its lower and upper ends as shown at 26^a and 26^b.

Attention is also drawn, as shown in Fig. 11, to the inserting of the side members 22 into the post construction of the car, whereby flush guide surfaces for the edges of the sash are obtained, even if the said side members extended upwardly only a limited distance.

I claim:

1. In car window construction, a frame comprising integral sill and side members, and a non-integral connection between the upper ends of the vertical members and the car letter-board.
2. In car window construction, a frame comprising integral sill and side members, and a non-integral connection between the upper ends of the vertical members and the car letter-board, the lower edge of the letter board deflected inwardly between the side members to form a lintel.
3. In car window construction, a frame comprising integral sill and side members, the car letter-board extending transversely of the upper ends of the vertical members, the letter board and side members lying in different parallel planes and connected by a finish member.
4. In car window construction, a frame comprising integral sill and side members, and a separate member connecting the upper ends of the side members, the sill having a forward extension beyond the side members and the side members angularly bent outwardly in opposite directions beyond the ends of the sill.
5. In car window construction, a frame comprising integral sill and side members, the sill having a forward extension beyond the side members and the side members angularly bent outwardly in opposite directions beyond the ends of the sill, and an outer finishing sheet overlying the car post and the outwardly turned portions of the side members.
6. In car window construction, a frame

comprising integral sill and side members, the sill having a forward extension beyond the side members and the side members angularly bent outwardly in opposite directions beyond the ends of the sill, an outer finishing sheet overlying the car post and the outwardly turned portions of the side members, and the forward extension of the sill, said finishing sheet being downturned over the edges of the sill and side frame members.

7. In car window construction, a frame comprising integral sill and side members, a non-integral connection part for the upper ends of the vertical members, a car letter-board, a hollow central window post resting on the sill and connected above to the letter-board, and a connecting member within the lower end of the post and secured to the sill and to the post.

8. In car window construction, the combination with a sliding sash, of a frame therefor comprising integral sill and side members and flanges formed integral with said side members and serving as stop members for guiding the sash.

9. In car window construction, the combination with a sliding sash, of a frame therefor comprising integral sill and side members, the side members having flanges formed integral therewith to serve as outer stop members for guiding the sash, and the sill having a flange formed integral therewith to serve as a sill step forming an inner abutment for the lower edge of the sash.

10. In car construction, the combination with a pair of posts and a letter board serving as a non-integral tie member therefor, and a sash lying between said posts, of a sash sill having integral upturned end members, the latter being so located as to provide flush guide ways for the edges of the sash.

11. In car window construction, a frame comprising integral sill and end members, and a vertical central member secured to said sill and providing a pair of window openings.

In witness whereof I have hereunto signed my name in the presence of two subscribing witnesses.

GEORGE H. FORSYTH.
